UNITED STATES PATENT OFFICE.

FRANK L. WRIGHT, OF CHICAGO, ILLINOIS, ASSIGNOR TO THE LUXFER
PRISM PATENTS COMPANY, OF SAME PLACE.

DESIGN FOR A PRISM-LIGHT.

SPECIFICATION forming part of Design No. 27,986, dated December 7, 1897.

Application filed October 22, 1897. Serial No. 656,098. Term of patent 14 years.

To all whom it may concern:

Be it known that I, FRANK L. WRIGHT, a citizen of the United States, residing at Chicago, in the county of Cook and State of Illinois, have invented a certain new and original Design for Prism-Lights, of which the following is a specification.

My invention relates to designs for prism-plates.

10 Figure 1 is a plan view of a prism-plate embodying my design. Fig. 2 is a section therethrough.

A is the body of the prism-plate.

15 B B are a series of surface areas substantially uniform in appearance and produced by the lines of separation C C, which cross the surface of the body of the plate. D D are prisms on the opposite side.

About the outer edge of the prism-plate are 20 a series of ornamental lines E E, produced on the outer surface areas and which have a distinct and characteristic form, so as to produce a sort of ornamental border for the prism-plate.

F F are ornamental lines produced on the 25 inner surface areas, each surface area having a design formed of such lines similar to the design on the other inner areas. Thus there is produced an inner field having a sort of mosaic appearance, with an outer border having a distinct ornamentation.

The essential features of my design are found in a prism-plate comprising a body with prisms on one side and a series of lines of separation on the other which divide it into a 35 series of substantially uniform surface areas, the outer areas ornamented to produce the effect of a border and the inner areas ornamented in a uniform manner so as to give the effect of an inner mosaic-like field.

40 I claim—

A design for a prism-plate, substantially as shown and described.

FRANK L. WRIGHT.
